GOLF BAG AND ACCESSORY THEREFOR

Harold Stuart Calkins, Wayland, Mich.

Application June 5, 1937, Serial No. 146,639

2 Claims. (Cl. 150—1.5)

This invention relates to golf bags and accessories therefor. It is particularly directed to a golf bag accessory at the open end of the bag for keeping the golf clubs from knocking together when within the bag.

5 An object of this invention is to provide a golf bag with accessory of the character described for holding the golf clubs upright and against movement whereby the stayed bag will stand up on 10 any fairly level place.

Still another object of this invention is to provide an accessory of the character described which may easily be detachably attached to golf bags now in use.

15 Yet another object of this invention is to provide a strong, rugged and durable golf bag accessory, which shall comprise few and simple parts, be relatively inexpensive to manufacture, and which shall yet be practical and efficient to 20 a high degree in use.

Other objects of this invention will in part be obvious and in part hereinafter pointed out.

The invention accordingly consists in the features of construction, combinations of elements, 25 and arrangement of parts which will be exemplified in the construction hereinafter described, and of which the scope of application will be indicated in the following claims.

20 In the accompanying drawing, in which is shown one of the various possible illustrative embodiments of this invention,

Fig. 1 is a side elevational view of the upper part of a golf bag provided with an accessory embodying the invention, with parts broken way in 35 cross-section; and

Fig. 2 is a top plan view of the golf bag and accessory.

Referring now in detail to the drawing, 10 designates a golf bag which may be of usual construction, and provided with an accessory 11 embodying the invention, assembled therewith in the novel manner hereinafter described.

The golf bag 10 comprises a generally cylindrical wall 12 having an upper rim edge 13. My improved accessory 11 for holding the golf clubs against knocking together and in upright position, comprises a cylindrical strap 14 of rubber or any other suitable material, having a longitudinal split 15 extending upwardly from a lower edge, substantially half way up. At the upper end of split 15, is a slot 16 or enlarged opening, crossing said split. The edges at the split 15 are provided with complementary fasteners 17 actuated by slider 18. The slider 18 is detachable

from one of the split edges, when moved to fully open position.

The lower portion of strap 14 receives the upper end of the golf bag. Within the upper portion of said strap and above the golf bag is a disc or plate 20 of resilient, compressible or flexible material such as sponge rubber. The periphery of disc 20 contacts the inner surface of strap 14 and may be vulcanized or otherwise attached thereto. The strap 14 forms a depending skirt 10 on plate 20 receiving the upper end of the golf bag.

Said disc or plate 20 is formed with a plurality of spaced vertical through openings 21, arranged in any suitable manner, preferably in circular rows of equiangularly spaced openings, with an additional central opening, so that the openings will be fairly equally distributed or balanced. The openings are preferably circular and of such dimension that when the handle of a club is inserted therethrough into the bag, the handle will be gripped by a yielding resilient pressure, as seen in Fig. 1.

In said figure there is shown a golf club 25 inserted into the bag through an opening 21 and held against slipping out or side-sway. When more than one club is inserted in to the bag, the clubs cannot knock together, thus preventing injury to the clubs and rattling.

As shown in the drawing, the usual carrying strap 26 of the golf bag 10 passes through the slot 16 adjacent the point where the upper end of said strap is attached to the golf bag. The slider actuated fasteners 17 close the slot 16 and hold the accessory 11 on the golf bag. The accessory 11 may be removed by pulling the slider 18 down and detaching the same from one of the edges of the split 15.

With my improved accessory the weight of the clubs in the bag is balanced, so that the bag may stand upright on any fairly level place.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim

as new and desire to secure by Letters Patent:

5 1. In combination, a golf bag, and a plate made of flexible, compressible material attached to the upper open end of the bag and entirely covering said open end, and being formed with spaced, through openings to receive golf clubs, and a depending skirt on said plate receiving the upper end of said golf bag, said skirt having a split extending up from its lower edge, and a 10 slot crossing the upper end of said split, a carrying strap on said golf bag passing through said

slot, and means for fastening together the edges of said split.

2. An accessory for a golf bag comprising a flat circular disc of sponge rubber, and a skirt of rubber vulcanized to the periphery of said disc and depending therefrom, said skirt having a split extending to the bottom edge thereof, and an enlarged opening at the upper end of said split, and means for attaching together the edges of said split.

HAROLD S. CALKINS. 10
